UNITED STATES PATENT OFFICE

ALBERT F. LAUDENSACK, OF NEW HAVEN, CONNECTICUT, ASSIGNOR TO WINCHESTER REPEATING ARMS COMPANY, OF NEW HAVEN, CONNECTICUT, A CORPORATION OF MARYLAND

MANUALLY-OPERATED BOLT-ACTION FIREARM

Application filed April 15, 1932. Serial No. 605,417.

This invention relates to an improvement in manually-operated bolt-action firearms, and particularly to that class of manually-operated bolt-action firearms having a so-called "upturn-and-pullback" bolt-action.

One of the major defects in upturn-and-pullback bolt-action firearms has been the occasional failure of a cartridge to be properly fed from the magazine into the cartridge-chamber. In different designs of firearms of this type, one or more factors contribute to this failure.

One of the primary objects of my present invention is to provide in a firearm of the class described, simple, convenient and reliable means for insuring the proper feeding of cartridges from the magazine into the cartridge-chamber.

With the above and other objects in view, as will appear from the following, my invention consists in a manually-operated upturn-and-pullback bolt-action firearm having certain features of construction and combinations and arrangements of parts as will hereinafter appear.

In the accompanying drawings:

Fig. 1 is a broken view in vertical longitudinal section, showing one form which a manually-operated upturn-and-pullback bolt-action firearm may assume in accordance with my invention, the bolt being shown near the limit of its forward movement, just prior to the locking of the same;

Fig. 2 is a similar view, partly in side elevation and showing the positions which the parts assume when the bolt is near the limit of its rearward movement, just prior to the ejection of the previously-fired and now empty cartridge-case;

Fig. 3 is a view corresponding to Fig. 2, but showing the bolt about half-way in its forward travel, during the feeding of a cartridge from the magazine-adapter into the cartridge-chamber of the barrel;

Fig. 4 is a transverse sectional view taken on the line 4-4 of Fig. 1;

Fig. 5 is a top or plan view of the unit comprising the magazine case, magazine-adapter and associated parts, detached;

Fig. 6 is an under-side view thereof;

Fig. 7 is a broken view in side elevation of the forward end of the bolt as removed from the receiver of the gun;

Fig. 8 is a view in rear-end elevation of the barrel, detached;

Fig. 9 is a perspective view of the magazine-adapter, detached;

Fig. 10 is a perspective view of the magazine case, detached;

Fig. 11 is a view in front end elevation of the ejector-unit, detached;

Fig. 12 is a view thereof in longitudinal section, taken on the line 12-12 of Fig. 11; and

Fig. 13 is a perspective view of the cartridge-pusher, detached, and

Fig. 14 is a detail view in vertical longitudinal section showing the rim of a cartridge seated against the conical recess in the gun-barrel.

The particular rifle herein chosen for the illustration of my invention is designed for the firing of high-power .22 calibre center-fire cartridges and consists, in the main, of a receiver 20 of substantially usual form provided in its upper face with an upwardly- and laterally-extending opening 21, through which cartridges are introduced downwardly into the magazine and through which empty cartridge-cases are laterally ejected in the usual manner of such firearms.

The forward end of the receiver 20 is formed with an internally-threaded socket 22 for the reception of an externally-threaded shank 23, rearwardly offsetting from the rear end of a rifle-barrel 24. The said receiver is also formed adjacent its upper end and axially in line with the barrel 24 with a longitudinally-extending guide-way 25 for the guidance of a reciprocating upturn-and-pullback bolt, generally designated by the numeral 26, and which may be, in its general features, of any approved construction.

The said bolt 26, as shown, is provided adjacent its forward end with the usual pair of laterally-offsetting locking-lugs 27-27 adapted to coact with forwardly-facing locking-shoulders 28-28 formed in the forward end of the receiver immediately adjacent the rear end of the barrel 24. The said bolt 26

100

is also provided adjacent its rear end with a laterally-offsetting operating-handle 29 by means of which the bolt is oscillated and reciprocated with respect to the gun-structure 5 for the purpose of locking and unlocking itself and for feeding cartridges from the magazine (to be hereinafter described) into the cartridge-chamber 30 having a shoulder 30^a and forming a feature of the barrel 24, 10 and also for the purpose of extracting empty cartridge-cases from the said chamber, all in substantial accordance with usual practice.

The receiver 20 is mounted upon the upper face of a gun-stock 31, which is recessed 15 on its upper face for the accommodation and definite positioning of the said receiver. The under-face of the gun-stock 31 has applied to it a guard-plate 32 having its rear end looped to form a trigger-guard 33, and its 20 forward end serving as a magazine floor-plate, as will hereinafter appear. Located over the said trigger-guard at the rear end of the plate 32 is a trigger-plate 34 provided with a longitudinal slot 35, through which 25 downwardly projects the lower end of a trigger 36.

The guard-plate 32, above referred to, is secured to the receiver 20 by a series of three (more or less) screws 37, 38 and 39, each of 30 which projects upwardly through the said plate 32 and is threaded into suitable threaded bores provided in the receiver 20. The two rearmost screws 37 and 38 also pass upwardly through the respective opposite ends 35 of the trigger-plate 34 and serve to position and hold the same in place.

Formed near the forward end of the receiver 20 in line with the opening 21 therein and below the path of travel of the bolt 26 40 is a vertical cartridge-feeding passage 40 leading downwardly into the interior of an upstanding rectangular sheet-metal magazine case 41. The upper end of the said magazine case is sleeved into a recess 42 formed 45 in the under-face of the said receiver 20, while the lower edge of the said magazine case rests upon the upper face of the guard-plate 32, the forward portion of which constitutes a magazine floor-plate, as before 50 pointed out.

The magazine case 41 is sufficiently large for the accommodation of large calibre cartridges, such as the ".30 government 06," and to adapt the same for the holding of smaller 55 cartridges such as high-power center-fire .22 calibre, I install in the forward portion of said magazine case 41 a sheet-metal magazine-adapter 43 of substantially-rectangular form and consisting, as herein shown, of an 60 upwardly- and forwardly-sloping front-wall 44 from which rearwardly offset two integral side-walls 45—45. Each of the said side-walls is provided at its rear edge with a pair of integral fingers 46, projecting through 65 correspondingly-spaced perforations 47

formed in a back-plate 48 and bent inwardly over the outer surface thereof. The back-plate 48 is upwardly and forwardly sloped in substantial parallelism with the front-wall 44 of the magazine-adapter, which latter is 70 adapted to accommodate a number of cartridges 49.

Each of the respective side-walls 45—45 of the adapter 43 is formed at its lower edge with an outwardly-offsetting positioning-flange 50, resting upon the upper surface of the guard-plate 32. Each of the said positioning-flanges 50 is provided with a pair of spaced-apart interlocking-projections or fingers 51—51 registering with and adapted 80 to enter similarly-spaced notches 52—52, a pair of which is formed in the lower edge of each of the complementary side-walls of the magazine case 41.

The positioning-flanges 50 and their complementary interlocking-fingers 51—51 serve to definitely position the magazine-adapter 43 within the magazine case 41 inasmuch as the said fingers 51—51, by their interengagement with the notches 52—52 of the magazine case 41, serve to interlock the said adapter with the said magazine case so as to prevent the former from moving upwardly, laterally or longitudinally with respect thereto, the guard-plate 32 normally serving to 90 prevent the downward displacement of the said adapter.

Installed within the magazine-adapter 43 is an inverted U-shaped sheet-metal follower 53 upon which the cartridges 49 rest and by which they are urged upward for successive feeding into the chamber 30 under the urge of a wire follower-spring 54. The said follower-spring is interposed between the under-face of the said follower and the upper face of the said guard-plate 32 and is preferably unattached to either the said follower or the said plate 32, as clearly shown in Figs. 1, 2 and 3 of the drawings.

Each of the respective opposite side-walls 45—45 of the magazine-adapter 43 is inwardly turned at its upper edge to form a longitudinally-extending cartridge-retaining lip 55. The two opposed complementary lips thus provided serve alternately to normally prevent the bodily upward egress of the cartridges 49 under the urge of the follower 53.

The upper end of the front-wall 44 of the magazine-adapter 43 is forwardly offset to form a guide-lip 56 which is preferably of transversely-bowed or trough-like form, as clearly shown in Fig. 5, to more or less conform to the transverse form of the cartridges. The said guide-lip 56 projects forwardly over the front-wall of the magazine case 41 into close proximity to a forwardly- and upwardly-sloping surface 57 formed upon the receiver 20 just immediately to the rear of the lower locking-shoulder 28 therein.

For the purpose of preventing the lateral

displacement of the upper end of the magazine-adapter 43, the forward wall of the magazine case 41 is suitably slotted and turned inwardly to form a pair of complementary retaining-fingers 58—58 engaging the respective opposite side-walls of the said adapter adjacent the guide-lip 56 thereof.

The bolt 26 may be of any approved form of the upturn-and-pullback type, but as herein shown, it is provided, in addition to its operating-handle 29, with a conically-contoured forward end 59 formed centrally with a recess-like cartridge-head seat 60 adapted to receive the head of a cartridge 49 and through which the firing-pin 61 carried by the said bolt, operates to fire a cartridge in the usual manner of bolt-action firearms. The conically-contoured forward end 59 of the said bolt 26 is adapted to substantially fit within a similarly-contoured combined cartridge-seating-and-guiding recess 62 formed in the rear end of the barrel 24, before referred to, and slopingly intersecting, without interruption, the rear end of the cartridge-chamber 30 therein.

At its forward end, the bolt 26 is formed in its periphery with a longitudinally-extending groove 63 intersecting its conical forward end 59 and receiving a retrievable pivotal cartridge-pusher 64 pivoted intermediate its forward and rear ends in the said groove upon a transverse pin 65, seated in the respective opposite side-walls of the said groove 63. The rear end of the said pusher 64 is slightly tapered on its inner edge as at 66, while the forward end thereof is provided with a T-shaped head 67, which latter is longitudinally slotted as at 68 to receive and straddle a guide-web 69 radially projecting from the forward end of the bottom of the groove 63 and formed integral with the bolt itself.

For the purpose of normally projecting the T-shaped head 67 of the said pusher outwardly, I provide the said pusher in its inner edge with a shallow pocket 69a receiving a helical spring 69b, the inner end of which bears against the bottom of the groove 63 before referred to.

The bolt 26 has also secured to it, in the usual manner of bolt-action firearms, a longitudinally-extending extractor 70, secured in place by means of the usual ring 71 and having at its forward end an inwardly-turned hook 72, normally slightly overhanging the cartridge-head seat 60 in the forward end of the said bolt and adapted to engage the forward face of the head of a cartridge for the purpose of extracting the same from the chamber 30 when the bolt 26 is drawn rearwardly.

For the purpose of ejecting a cartridge laterally through the side of the opening 21 in the receiver, as will hereinafter appear, I provide a pivotal ejector 73 which instead of

being mounted directly in the receiver in accordance with the usual practice, is pivotally mounted, by means of a pin 74, in a block-like ejector-holder 75, mounted, and secured by means of rivets 76, in the upper end of the magazine case 41, between the rear wall thereof and the rear wall of the magazine-adapter 43. The said ejector 73 is pivoted, as described, adjacent its rear end and is provided with an ejector-nose 77 adapted to be engaged by the rear end of a cartridge as the same is drawn rearwardly with the bolt, and the latter approaches the limit of its rearward movement.

The forward end of the ejector 73 is normally urged outward so as to project its nose 77 into the path of the head of the cartridge, as above described, by means of a helical spring 78 having its outer end seated in a notch 79 in the inner edge of the said ejector 73, while its inner end is seated in a shallow pocket 80, leading out of the bottom of the longitudinal groove 81 in which the said ejector is located in the said holder.

The rearward travel of the bolt 26 is normally limited, for the purpose as will hereinafter appear, by providing the said bolt with a rearwardly-facing stop-shoulder 82 which is adapted to engage the forward face of a sear-nose 83 forming a usual feature of a sear 84, which latter is actuated in the usual manner by the trigger 36, before referred to.

For the purpose of making clear the functioning of the parts before described, let it be presumed that the bolt 26 is at the limit of its rearward travel, with its stop-shoulder 82 engaged with the sear-nose 83. In this position of the parts, the said bolt will occupy a position but slightly to the rear of the position in which it is shown in Fig. 2, and it will be noted that the conically-contoured forward end 59 of the said bolt extends forward slightly over the rear end of the magazine-adapter 43. Cartridges may now be successively fed downwardly into the said magazine-adapter 43 through the opening 21 and cartridge-feeding passage 40 in the receiver 20, and will pile up in the said adapter much in the manner shown in Fig. 1 of the drawings, being held against upward expulsion by one or the other of the overhanging cartridge-retaining lips 55.

By stopping the rearward movement of the bolt in such position that its forward end slightly overhangs the rear wall 48 of the adapter 43, each cartridge, as the same is forced into the adapter, will automatically have its head positioned forwardly of the head of the preceding cartridge, to thus insure the freedom for forward travel of each cartridge as it reaches the uppermost position in the said adapter.

If now the bolt 26 be manually forced forwardly, the forward face of the now project-

ing T-shaped head 67 of the cartridge-pusher 64 will engage the rear face of the then uppermost cartridge 49 and force the same forwardly toward the chamber 30. As a given cartridge 5 is being thus forced forwardly, its forward end will slide through the cartridge guiding-lip 56 at the forward end of the adapter 43 to thus be more or less centered thereby and prevented from unduly canting 10 laterally and, in addition, prevented from dipping downwardly.

As a further precaution to insure the proper entry of the bullet end of a given cartridge into the chamber 30, the conically-contoured 15 recess 62 before referred to is provided. Thus, if for any reason during the forward movement of the cartridge now being described, the bullet end of the cartridge should become unduly lifted, the upper portion of 20 the said recess 62 will serve to guide the said bullet end downwardly toward the open rear end of the chamber 30. It will be understood, of course, that the instant the head end of the cartridge clears the forward end 25 of the lips 55 of the adapter 43, the said rear end will rise under the urge of the follower 53 and thereby assume a less inclined position to further facilitate the entry of the bullet end into the chamber 30.

With the bullet end of the cartridge started 30 into the open rear end of the chamber 30, a continued forward movement of the bolt 26 and its ultimate oscillation by swinging its handle 29 downward, will serve to firmly 35 seat the said cartridge therein, preparatory to discharging the gun.

It will be noted that the surface of the conical recess 62 directly intersects the rear end of the chamber 30, so that when a cartridge 39 is pushed home in the said chamber, the forward corner of its head will seat against the cone-like surface of the said recess before the shoulder of the said cartridge can reach the shoulder 30^a of the cartridge-chamber 30. In other words, no specially cut 45 head-seat is provided which would form a ledge against which the bullet end of the cartridge might catch and thus jam. The discharge of the gun may be effected in the usual 50 manner by means of the trigger 36 which serves to release the firing-pin 61.

During the forward travel of the bolt, as 55 just above described, the forward end of the cartridge-pusher 64 will be engaged with the cartridge-guiding lip 56 of the magazine-adapter 43, but owing to its retrievable character (it being pivoted, as already described), it will ride smoothly over the said surface 60 without affording any appreciable hindrance to the travel of the bolt.

After a cartridge has been fired, the handle 29 of the bolt 26 is upturned for the purpose of unlocking the bolt, after which the bolt is drawn rearwardly by means of the 65 said handle, carrying with it, through the in-

termediary of the extractor 70, the now empty cartridge-case.

When in the rearward travel of the bolt, the rear end of the cartridge-case is engaged with the forward edge of the ejector-nose 77, the empty cartridge-case will be "flipped," so to speak, laterally outward through the side of the opening 21 in the receiver 20 in the usual manner of bolt-action firearms. 75

With the empty cartridge-case thus ejected and the bolt in its rearmost position, the gun is now in condition for another cycle of operation.

It will be understood by those skilled in the art that my invention may assume varied physical forms without departing from my inventive concept and I, therefore, do not limit myself to the specific embodiment herein chosen for illustration, but only as indicated in the appended claims. 85

I claim:

1. In a manually-operated, upturn-and-pullback, bolt-action firearm, the combination with the bolt thereof having a slot opening through its forward end; of a retrievable cartridge-pusher pivotally mounted in the slot in the said bolt and having a slotted forward end engageable with a cartridge for feeding the same into the cartridge-chamber of the firearm upon a forward movement of the said bolt; and guide-means carried by the said bolt and projecting into the slot in the forward end of the said cartridge-pusher for guiding the same. 90

2. In a manually-operated, upturn-and-pullback, bolt-action firearm, the combination with the bolt thereof having a slot opening through its forward end; of a retrievable cartridge-pusher pivotally mounted in the slot in the said bolt and having a slotted forward end engageable with a cartridge for feeding the same into the cartridge-chamber of the firearm upon a forward movement of the said bolt; and an integral tongue offsetting from the said bolt and projecting into the slot in the forward end of the said cartridge-pusher for guiding the same. 105

3. In a manually-operated, upturn-and-pullback, bolt-action firearm, the combination with the receiver thereof; of a magazine case associated with the said receiver; a magazine-adapter installed in the forward end of the said magazine case; and an ejector carried by the said magazine case at a point to the rear of the said magazine-adapter. 115

4. In a manually-operated, upturn-and-pullback, bolt-action firearm, the combination with the receiver thereof; of a magazine case associated with the said receiver; a magazine-adapter installed in the forward end of the said magazine case; and an oscillating ejector secured to the said magazine case at a point to the rear of the said magazine-adapter. 125

5. In a manually-operated, upturn-and-pullback, bolt-action firearm, the combination with the receiver thereof; of a magazine case associated with the said receiver; 5 a magazine-adapter installed in the forward end of the said magazine case; an ejector-holder carried by the said magazine case at a point to the rear of the said magazine-adapter therein; and an ejector carried by the said 10 ejector-holder.

6. In a manually-operated, upturn-and-pullback, bolt-action firearm, the combination with the receiver thereof; of a magazine case associated with the said receiver; a magazine-adapter located within the forward end of the said magazine case; and positioning-means carried by the forward wall of the said magazine case and engageable with the said magazine-adapter adjacent the upper 15 portion thereof for holding the same against lateral displacement.

7. In a manually-operated, upturn-and-pullback, bolt-action firearm, the combination with the receiver thereof; of a magazine case associated with the said receiver; a magazine-adapter located within the forward end of the said magazine case; and positioning-means offsetting from the lower end of the said magazine-adapter and engageable with 20 the said magazine case adjacent the lower end thereof.

8. In a manually-operated, upturn-and-pullback, bolt-action firearm, the combination with the receiver thereof; of a magazine case associated with the said receiver and formed in its lower edge with notches; a magazine-adapter installed within the said magazine case and having projections offsetting into the notches in the said magazine 25 case for interlocking the latter and the said adapter.

In testimony whereof, I have signed this specification.

ALBERT F. LAUDENSACK.
